UNITED STATES PATENT OFFICE.

WILLIAM C. BAXTER, OF BEVERLY, MASSACHUSETTS, ASSIGNOR TO UNITED SHOE MANUFACTURING CORPORATION, OF PATERSON, NEW JERSEY, A CORPORATION OF NEW JERSEY.

MACHINE FOR USE IN THE MANUFACTURE OF SHOES.

Application filed May 6, 1925, Serial No. 28,389, and in Great Britain May 19, 1924. Renewed May 26, 1928.

This invention relates to machines for use in the manufacture of boots and shoes for shaping the upper materials, and is herein illustrated in its application to a machine 5 of the type shown and described in Letters Patent No. 1,692,284, granted upon my application on November 20, 1928, having means for molding the toe of the upper off the last substantially to the shape desired 10 for the finished shoe. It is to be understood, however, that in various novel and useful aspects the invention is not limited to machines of that particular type, nor to machines for shaping an upper over a form of 15 the character herein illustrated as distinguished from a different kind of form such, for example, as a last.

In shaping or molding the toe of an upper over a form it is important that the work be 20 accomplished in such manner that the contour of the toe will bear the proper relation to other portions of the shoe. It is particularly important, where uppers are provided with tips, that the tip line be located at the 25 proper distance from the end of the toe and lie substantially in a plane extending in proper angular relation to the throat of the vamp and to the bottom of the shoe. It is also necessary, for satisfactory results, that 30 the upper be shaped smoothly to the contour of the form without the presence of wrinkles in any portion that is visible in the finished shoe.

The present invention has particularly in 35 view the provision of means for controlling the upper in the upper-shaping or molding operation in such manner as to accomplish the best results in the different respects above mentioned. To this end, the invention provides 40 a novel organization including devices for engaging the upper at the opposite sides of the toe and for thus holding it against undesirable displacement relatively to the form in the molding operation. As herein illustrated, grippers are provided which grip the upper at the opposite ends of the tip seam and are movable inwardly toward the form in response to the pull of the upper thereon as the upper is shaped about the 45 form, the grippers being so controlled as to move in predetermined directions unaffected by the directions of the tensions arising in the upper and thus to prevent uncontrolled movement lengthwise of the form of the por-

tions of the upper which they engage. As 55 applied to an organization of the type shown, for example, in the above-mentioned Letters Patent, including wipers which wipe the upper inwardly over the form to mold a marginal flange thereon, the grippers as 60 herein shown are so controlled as to maintain their hold upon the upper with sufficient pressure for the purposes in view until the wipers have arrived substantially or approximately at the end of their inward wiping movement. In this manner effective control of the margin of the upper at the opposite ends of the tip seam is afforded substantially throughout the upper-molding 65 operation so that the end portions of the 70 tip seam at the opposite sides of the toe will no be forced rearwardly by the wipers or be otherwise improperly displaced but will be positioned in the proper predetermined relation to other parts of the shoe. In the 75 construction shown the grippers are mounted to swing directly toward each other laterally of the form, or in directions substantially perpendicular to the longitudinal median line of the form, so that they hold the upper 80 at the ends of the tip seam from any shifting movement lengthwise of the form during the molding.

In the shaping or molding of the toe of an upper over a form there is, of course, a 85 tendency for pleats or wrinkles to form in its marginal portion as the latter is contracted about the form, especially in that part which is to be trimmed off after the molding. In a further important aspect, 90 the invention aims to prevent excessive or undue wrinkling at any point, such as might interfere with the shaping of the upper smoothly over the form, and to this end the invention provides novel means for controlling 95 the marginal portion of the upper in such manner as to predetermine or regulate the formation of wrinkles or pleats. The construction shown comprises members for clamping the marginal portion of the upper upon the wipers while permitting the clamped portion to slip inwardly toward the form as required in response to tensions arising in the upper as it is shaped over the 100 form, the clamp members having in their 105 upper-engaging faces a plurality of grooves in which wrinkles are permitted to form as the fullness develops along the marginal

portion of the upper in the course of the molding operation. By thus providing spaces in predetermined locations for the formation of the wrinkles, danger is avoided 5 of undesirable shifting of the clamped marginal portion of the upper lengthwise of the edges of the wipers at any point in response to the strains thereon, or of undue wrinkling beyond the ends of the clamp members. In 10 combination, moreover, with the means described for gripping and holding the margin of the upper substantially at the ends of the tip seam, the means provided for localizing or regulating the formation of pleats in the 15 margin of the upper contributes effectively to the general end in view, namely to afford accurate control of the position of the upper during the molding.

In the machine herein shown, as in the 20 disclosure of the Letters Patent mentioned, the upper-shaping form receives a swinging movement relatively to co-operating upper-shaping instrumentalities during a portion of the shaping or molding operation while 25 pressing the top or intermediate portion of the toe of the upper upon a toe rest or support which yields in response to the pressure of the form. In accordance with a further feature of the invention the toe rest is 30 mounted to swing about the same axis as the form, thus insuring against any drag of the toe rest on the top of the forepart of the upper in the molding operation. This 35 construction is also particularly useful where, as herein shown, the toe rest or support has a shape substantially complementary to that part of the form which is opposite thereto, since it insures against relative 40 shifting of the two complementally shaped forming members.

The above and other features of the invention, including also novel means for applying wiping and holding pressure to the upper about the end and the sides of the 45 form, novel means for detaching the molded upper from the form, and various details of construction and combinations of parts will now be more particularly described by 50 reference to the accompanying drawings and thereafter pointed out in the claims.

In the drawings,

Fig. 1 is a view in side elevation of the upper portion of a machine in which the invention is embodied, with parts of the structure broken away to illustrate details;

Fig. 2 is a view in front elevation of the structure shown in Fig. 1, with parts broken away;

Fig. 3 is a plan view of a portion of the 60 machine, with parts broken away to show more clearly what lies beneath;

Fig. 4 shows an upper mounted on a presenter for use in presenting the upper to the machine;

Fig. 5 is a view in front elevation and

partly in section of the upper-molding instrumentalities, illustrating how the upper is presented to the machine;

Fig. 6 is a view similar to Fig. 5 showing the parts in the positions that they occupy 70 at an intermediate point in the downward movement of the form;

Fig. 7 shows the parts as positioned when the wipers have substantially completed their 75 inward wiping movement; and

Fig. 8 shows the parts as positioned while the upper is being held by the wipers to permit it to set in molded shape.

As more fully shown and described in the Letters Patent mentioned, the machine comprises an inner toe form 2 carried by an arm 4 which is mounted at 6 on the head of the machine for upward and downward swinging movements, the form being so constructed as to mold the toe portion of the upper 85 substantially to the shape desired for the finished shoe. The arm 4 is connected by an operating bar 8 and a rod 10 to a lever 12 controlled by a cam (not shown) on a cam shaft 14, whereby downward swinging 90 movement is imparted positively to the form 2 relatively to means for wiping the upper upwardly about the end and the sides of the form. At a later stage in the cycle reverse movement is imparted to the rod 10 95 to press the form upwardly against wipers 15 which wipe the margin of the upper inwardly over the form, thus increasing the downward pressure of the wipers upon the marginal portion of the upper, a spring 16 100 being interposed between the end of the bar 8 and a collar on the rod 10 to render this pressure yielding.

The upwiping is effected by means of a toe band 18 which is in position to embrace 105 the end and the sides of the form 2 as the form is depressed. The toe band 18 is controlled by mechanism more fully shown and described in the prior Letters Patent, whereby it is advanced and closed to bring it into 110 operative wiping position and is also retracted and opened, this mechanism including a bell-crank 20 (Fig. 1) connected by a link 22 to a lever 24 provided with a roll 25 which is controlled by a cam 26, more fully 115 hereinafter described, on the cam shaft 14.

Prior to the downward movement of the form the upper *a* is presented to the machine by the use of a presenter 28 (Fig. 4) which is provided with upturned jig pins 30 for engaging the upper in jig holes formed in its margin substantially at the opposite ends of the tip seam *b*, these jig pins being arranged to enter slots 32 (Fig. 3) in the wipers 15 to insure an accurately predetermined relation 125 of the upper to the molding instrumentalities. The toe of the upper is thus outspread substantially in a plane with its margin over the top or outer faces of the wipers. Before the form in its downward movement arrives 130

in position to engage the upper, the marginal portion of the latter is clamped upon the top of the wipers 15 by means of clamp members 36, and the presenter 28 is removed from engagement with the upper, these clamp members assisting in drawing the upper tightly about the form while permitting it to slip inwardly toward the form as required in response to tensions arising in the upper. 10 It will be understood that after the form has completed its downward movement the wipers are advanced and closed to wipe the marginal portion of the upper inwardly over the form and, as herein shown, to mold it in 15 angular shape against co-operating faces of the form to provide a flange adapted for attachment to a welt shoe insole. As described in the prior Letters Patent, the wipers are thus advanced and closed by mechanism including a toggle 38 connected by a link 40 to a lever 42 operated by a cam on the cam shaft 14.

Beneath the form 2 is a toe rest or support 44 which, in the construction herein shown, 25 comprises a metal block the upper face of which has a contour substantially complementary to that face of the form which is opposite thereto and is preferably provided with a leather facing 46 for engagement 30 with the upper. The toe rest thus serves as a complementary outer form and is shaped to engage substantially the whole of the top of the forepart of the upper which is out of range of the wiping action of the toe band 35 18. The toe rest 44 in the construction herein shown is mounted upon the upper end of a curved plunger 48 which is movable in a similarly curved guideway formed in a casing 50 supported on the end of an arm 52. 40 The plunger 48 is provided with rack teeth 54 in engagement with a pinion 56 which is mounted on a spindle 58 in the casing 50, the spindle having fast thereon a pair of lever arms 60 controlled by springs 62 which 45 are connected respectively to said arms and to pins 64 on the casing. It will be seen that the springs 62 thus hold the toe rest 44 yieldingly in its uppermost position, this position of the rest being adjustably determined by a stop screw 66 on the casing 50 in engagement with one of the arms 60. Preferably the toe rest will be positioned, as shown, with its upper-engaging face about 55 on a level with the wipers 15. The toe rest 44 is pivotally mounted on the upper end of the plunger 48 and may tip lengthwise of the form against the resistance of curved leaf springs 68 to permit it to bear evenly upon the different portions of the upper. It will 60 be understood that in the downward movement of the form 2 the top of the forepart of the upper is pressed upon the toe rest 44, and as the form continues its downward movement the toe rest is moved downwardly 65 with it. The plunger 48 and its guideway

are curved in an arc the center of which is the same as the axis 6 about which the form 2 swings, so that there is no relative movement between the toe rest and the form after the upper has been clamped between these 70 parts and, therefore, no tendency to displace the upper relatively to the form by reason of any drag on the top of the forepart.

The clamp members 36 in the construction herein shown terminate at a short distance 75 from the tip line of the upper, and the machine is provided with grippers which grip the margin of the upper at and near the ends of the tip seam beyond the ends of the clamp members. Each of these grippers 80 comprises a pair of jaws 70 and 72, the lower jaw 70 being fast on a gripper bar 74 which is secured at its upper end to an arm 76 pivotally mounted at 78 upon a bracket 80 on the head of the machine. The jaw 85 72 is fast on a slide 82 which is guided for upward and downward movements by a rib 84 on the bar 74 and has at its upper end a head 86 provided with a transverse groove 88. In the groove 88 is mounted a roll 90 90 which is carried by an arm 92 fast on a rock shaft 94. Movements of the jaw 72 toward and from the jaw 70 are thus effected by the rocking of the shaft 94. The arm 76 at its outer end is engaged and uplifted by a 95 spring 96 the lower end of which is seated in a socket formed in a lug 98 on the bracket 80. The spring 96 thus serves to swing the gripper outwardly, and is yieldable to permit it to swing inwardly toward the form 100 2 in response to the pull of the upper thereon. To limit the outward swinging movement of the gripper the arm 92 carries a limit stop comprising a plate 100 provided with arms of different lengths any one of which may be moved into position to serve as an abutment in engagement with the gripper bar 74. The plate 100 is secured to a rod 102 which projects downwardly 105 through the arm 92 and has at its lower end an enlarged head 104 between which and the inner end of a socket in the arm 102 is mounted a spring 106. By pressing up on the head 104 and turning it the member 100 110 may be moved to bring any one of its arms opposite to the bar 74. It is desired to position the grippers with their jaws close to the inner ends of the slots 32 in the wipers, so that they will grip the upper adjacent to the jig holes which are formed therein, and since the positions of these slots will vary as different wipers are substituted for different sizes or styles of uppers, the members 100 are utilized as described to position the grippers in the proper relation to the different wipers. It will be observed that the lower gripper jaw 70 is positioned close to the top face of the wipers with only enough clearance to prevent interference between the jaw and the wipers as the arm is swung 115 120 125 130

about its pivot 78. It will also be understood that the groove 88 is so inclined as to permit the gripper to swing about the pivot 78 relatively to the roll 90 without any substantial effect upon the gripping pressure applied to the upper.

The clamp members 36 also are moved into and out of upper-clamping position by rocking movements of the respective rock shafts 94. Each clamp member is pivotally mounted on the inner end of an arm 108 which at its outer end is provided with pins 110 guided in slots 112 in members 114 that are fast on the head of the machine. Near its inner end each of the arms 108 is connected by links 116 to the members 114, so that when the clamp member is moved downwardly toward the wipers it is also swung inwardly to bring it close to the edges of the wipers. Each arm 108 is connected by a link 118, through ball-and-socket joints, to an arm 120 which is loosely mounted on the shaft 94. Secured adjustably to the shaft 94 by means of a set screw 122 is an angular bracket member 124 in one arm of which is an adjustable stop screw 126 which supports the arm 120. In the other arm of the bracket member 124 is adjustably mounted a screw 128 which bears on a spring plunger 130 in the arm 120. A yielding connection is thus afforded between each of the arms 120 and the corresponding rock shaft 94 so that clamping pressure is applied yieldingly to the upper by the clamp members 36. It will also be evident that the force of the clamping pressure applied by either of the clamp members may be varied by adjusting the corresponding screw 128.

The rock shafts 94 are provided at their rear ends with gear segments 132 which are engaged by beveled gears 134 fast on short transverse shafts 136. The shafts 136 are connected by gearing 137 to a shaft 135 provided with a lever arm 138 connected by a link 140 to a lever 142 which is pivoted at 144 on the frame of the machine and is provided with a roll 146 engaged by a cam 148 on the shaft 14. A spring 150 is provided for moving the link 140 downwardly and thereby holding the roll 146 in engagement with the cam. It will be understood that when the link 140 is moved upwardly by the cam the clamp members and the grippers are operated to clamp and to grip the upper as above described, the clamp members being operated yieldingly through the spring plungers 130 while the grippers are closed positively upon the upper materials. The force with which the upper is gripped by the gripper jaws 70 and 72 may be varied, for example, by varying the length of the link 140 through a turnbuckle 152, while the amount of resistance to the inward swinging movements of the grippers may be varied

by means of adjusting screws 154 which determine the tensions of the springs 96.

By reference to Fig. 1 it will be seen that the cam 148 is so shaped that upon the starting of the machine the clamp members 36 and the grippers are operated respectively to clamp the marginal portion of the upper upon the top of the wipers and to grip it at the ends of the tip seam, and it will be understood that as the form 2 is moved downwardly the grippers are swung inwardly toward the form in response to tensions arising in the upper but in directions unaffected by the directions of said tensions, while the clamp members permit the portions of the upper engaged thereby to slip and move inwardly toward the form while applying thereto sufficient pressure to draw the upper tightly about the form. The gripper jaws 70 and 72 are provided with serrated gripping faces, so that they hold the upper from slipping as the form is moved downwardly, and the opposite grippers in the construction shown are mounted to swing directly toward each other so that they hold the upper at the ends of the tip seam against any movement lengthwise of the form. Substantially at that point in the cycle when the wipers 15 begin their inward wiping movement a slight declivity shown at *c* on the cam 148 serves to relax the pressure of the clamp members 36 upon the upper and thus to permit it to slip more freely as it is wiped inwardly over the form, although these members remain in position to hold the upper drawn tightly over the edges of the wipers as the latter are moved inwardly.

As the pressure of the clamp members is thus relaxed, the pressure of the gripper jaws upon the upper is also somewhat relaxed, but the latter by their serrated faces maintain a sufficient hold on the upper to prevent any substantial displacement of the portions at the ends of the tip seam lengthwise of the form, although the margin of the upper may slip somewhat inwardly through the gripper jaws in response to the pull of the wipers thereon. When the wipers have arrived approximately at the end of their operative movement, or in position to bend the margin of the upper over the edge of the form and thus secure a firm hold thereon, a further declivity *d* in the cam 148 causes the clamp members 36 to be withdrawn to inoperative position and the grippers to open and release the upper.

In the construction herein shown the clamp members 36 have formed in their generally plane upper-engaging faces a series of grooves 156 which radiate outwardly from the form 2 and thus extend in substantially the same directions as the lines of force or tension to which the different respective portions of the margin of the upper are sub-

jected as the upper is shaped over the form. The grooves 156 thus provide spaces permitting the formation of wrinkles or pleats in the margin of the upper and determining the 5 locations of the pleats as fullness develops along the margin while the latter is being contracted inwardly toward the form. Insurance is thus afforded against undesirable shifting of the clamped portion of the margin of the upper lengthwise of the edges of 10 the wipers and against excessive wrinkling at any point along the margin. It will be observed that the grooves 156 terminate short of the inner edges of the clamp members 36, so that while the full clamping pressure is being applied during the downward 15 movement of the form the clamp members by their plane faces co-operate with the wipers in laying the upper smoothly about the end and the sides of the form. When 20 the clamping pressure is relaxed at the beginning of the inward movement of the wipers 15 the wrinkles are permitted to form still more freely in the grooves 156, and 25 when the clamp members are finally lifted the wrinkles or pleats extend in a regular series along that portion of the margin of the upper which is to project upwardly from the bottom of the form and is subsequently 30 to be trimmed.

The machine herein shown is provided with means for controlling the toe band 18 in such manner as to increase the pressure of the band on the upper after the upwiping has been effected in response to the downward movement of the form. As shown on 35 Fig. 1 the cam 26 is provided with a rise at *e* for this purpose, the increased pressure being yieldingly applied through the provision of a spring 158 forming a connection 40 between the link 22 and the bell-crank 20. Additional insurance is thus afforded that the upper will be held effectively about the end and the sides of the form when the pressure of the clamp members 36 is relaxed at 45 the beginning of the inward movement of the wipers. After the wipers have completed their inward movement a declivity shown at *f* in the cam 26 causes the toe band 18 to withdraw from pressure-applying relation to the upper in order to avoid any possible danger of marking the upper during the time that the upper is held by the wipers 50 to permit it to set in molded shape.

The machine is also provided with means 55 for detaching the molded toe from the form 2. Extending lengthwise of the form is a spring plunger 160 provided with an end portion 162 adapted to be projected forwardly from the contour face of the end of the form. At its outer end the plunger 160 is arranged to be engaged by the end of an 60 adjustable screw 164 carried by a lever 166 which is pivoted at 168 on the arm 4. At its 65 upper end the lever 166 is connected by a

link 170 to a slide 172 mounted in a guide-way on the arm 4. The slide 172 carries a roll 174 which is arranged to engage a cam face 176 on an arm 178 secured to the head of the machine. When the arm 4 is swung upwardly after the molding of the toe the cam face 176 acts on the roll 174 and through the connections described forces the plunger 160 forwardly in the form to detach the molded toe in case the toe should stick to the 75 form.

In the operation of the machine, briefly summarized, the upper is mounted on the presenter 28, as illustrated in Fig. 4, and is presented to the machine in the manner illustrated in Fig. 5, the jig pins 30 of the presenter being moved to the inner ends of the slots 32 in the wipers 15 and the marginal portion of the upper thus being outspread over the top face of the wipers with portions adjacent to the jig pins extending over the gripping jaws 70. Upon the starting of the machine the clamp members 36 are moved downwardly to clamp the upper upon the top of the wipers and the gripper jaws 72 are moved downwardly to grip the upper at 80 the ends of the tip seam adjacent to the jig pins. After the upper has been thus clamped and gripped the presenter 28 is removed by the operator, and the form 2 in its downward movement comes into engagement with the intermediate portion of the outspread upper and presses it upon the toe rest or outer form member 44. As the form continues its downward movement the toe rest 44 is 85 moved therewith about the same axis and the upper is wiped upwardly about the end and the sides of the form by the toe band 18 in the manner illustrated in Fig. 6. During the upwiping operation the marginal portion of the upper is permitted to slip inwardly toward the form between the clamp members 36 and the wipers as required in response to the pull thereon, the grooves 156 90 in the clamp members localizing any wrinkles or pleats that tend to form at this time in response to the increasing fullness of the margin of the upper. At the same time the grippers, which hold the upper with an unslipping grip, are swung inwardly against the resistance of the springs 96 in response to the pull of the upper thereon, thus preventing any displacement lengthwise of the 95 form of the portions of the upper at the ends of the tip seam.

When the form 2 arrives at the end of its downward movement the pressure of the toe band 18 upon the upper is increased and the pressure of the clamp members 36 and of the grippers upon the margin of the upper is 100 somewhat relaxed. The wipers 15 are then moved inwardly to wipe the upper over the edge of the form and to mold an angularly shaped marginal flange thereon. During 105 this inward movement of the wipers the 110

clamp members 36 permit the upper to slip more freely than in the upwiping operation, although continuing to hold the upper drawn tightly across the edges of the wipers, and the upper also may slip inwardly to some extent between the gripper jaws 70 and 72, although the latter continue to hold the upper with sufficient pressure to prevent undesirable displacement of its marginal portion lengthwise of the form. When the wipers 15 have arrived substantially or nearly at the end of their operative movement and have secured an effective hold upon the upper by bending it over the edge of the form, as illustrated in Fig. 7, the clamp members 36 are raised to release the upper completely and the grippers are opened and are swung outwardly by their springs 96. After the wipers have completed their operative movement the band 18 is opened to release the upper from pressure about the end and the sides of the form, as illustrated in Fig. 8, the form being pressed upward yieldingly to increase the downward pressure of the wipers on the upper. Thereafter the upper is held by the wipers for a sufficient time to permit it to set in molded shape, and in the meantime the surplus margin of the flange on the upper projecting above the bottom face of the form is trimmed off by the operation of trimming means such as described in the Letters Patent hereinbefore mentioned. After the trimming operation the machine comes automatically to a stop, and when the operator starts it again the parts are returned to starting positions, the form 2 being swung upwardly with the upper thereon. In the upward movement of the form the detaching mechanism is operated by the cam face 176 to detach the upper from the form and permit it to be readily removed by the operator.

While the invention is herein illustrated in its application to a machine particularly designed for molding the toes of welt shoe uppers, it is to be understood that the invention is not thus limited in its applicability.

Having described the invention, what I claim as new and desire to secure by Letters Patent of the United States is:

1. In a machine of the class described, the combination with means for shaping the toe portion of an upper over the end and the sides of a form, of means for engaging the margin of the upper at the opposite sides of the toe substantially in the location of the tip line and for holding the portions thus engaged from shifting lengthwise of the form in the upper-shaping operation.

2. In a machine of the class described, the combination with wiping means for shaping the toe portion of an upper over a form, of means for engaging the margin of the upper

per at the opposite sides of the toe and for holding the portions thus engaged from uncontrolled movement lengthwise of the form in the upper-shaping operation, said upper-engaging means being movable inwardly toward the form in response to the pull of the upper thereon. 70

3. In a machine of the class described, the combination with means for shaping the toe portion of an upper over a form, of means for engaging the margin of the upper substantially at the ends of the tip seam, said upper-engaging means being movable inwardly toward the form in response to the pull of the upper thereon while holding the ends of the tip seam from displacement lengthwise of the form. 75

4. In a machine of the class described, the combination with means for shaping the toe portion of an upper over the end and the sides of a form and for wiping its margin inwardly over the form, of means for engaging the margin of the upper at the opposite sides of the toe and for holding the portions thus engaged from uncontrolled movement lengthwise of the form as the upper is shaped and wiped over the form. 80

5. In a machine of the class described, the combination with means for shaping the toe portion of an upper over a form, of grippers for gripping the margin of the upper at the opposite sides of the toe substantially at the ends of the tip seam, said grippers being mounted to move inwardly toward the form in fixed paths in response to the pull of the upper thereon while holding the portions of the upper which they engage from uncontrolled movement lengthwise of the form. 90

6. In a machine of the class described, the combination with means for shaping the toe portion of an upper over a form having a contour corresponding substantially to that of the toe end of the finished shoe, of grippers for gripping the margin of the upper at the opposite sides of the toe, said grippers being movable inwardly toward the form in response to tensions arising in the upper as it is shaped over the form, and means constraining said grippers to move in predetermined directions that are unaffected by the directions of said tensions. 105

7. In a machine of the class described, the combination with means for shaping the toe portion of an upper over a form, of grippers for gripping the margin of the upper substantially at the ends of the tip seam and for holding the portions thus gripped from uncontrolled movement lengthwise of the form in the upper-shaping operation, said grippers being movable inwardly toward the form in fixed paths in response to the pull of the upper thereon, and spring means against the resistance of which the grippers are thus inwardly movable. 120

8. In a machine of the class described, the 125

combination with means for shaping the toe portion of an upper over a form, of grippers for gripping the margin of the upper at the opposite sides of the toe and for holding the portions thus gripped from uncontrolled movement lengthwise of the form in the upper-shaping operation, said grippers being mounted to swing inwardly toward the form about axes extending lengthwise of the form in response to the pull of the upper thereon, and spring means against the resistance of which the grippers are thus inwardly movable.

9. In a machine for shaping the toe portion of an upper over a form, grippers for gripping the margin of the upper at the opposite sides of the toe substantially in the tip line location with the toe of the upper outspread substantially in a plane, means for effecting relative movement of said grippers and the form to tension the upper over the form, said grippers being movable inwardly toward the sides of the form in response to the pull of the upper thereon while holding the portions of the upper which they engage from uncontrolled movement lengthwise of the form, and spring means tending to force said grippers outwardly from the form while permitting them to be moved inwardly by the pull of the upper.

10. In a machine for shaping the toe portion of an upper over a form, means for wiping the upper over the end and the sides of the form in response to relative movement of the form and said wiping means heightwise of the form, grippers at the opposite sides of the form for gripping the margin of the upper prior to said relative movement, said grippers being movable inwardly toward the form in fixed paths in response to the pull of the upper thereon while preventing in the wiping operation uncontrolled movement lengthwise of the form of the portions of the upper which they engage, and spring means tending to force said grippers outwardly while permitting them to be moved inwardly by the pull of the upper.

11. In a machine of the class described, the combination with wiping means for shaping the toe portion of an upper over a form by relative movement of the form and said wiping means heightwise of the form, of grippers for gripping the margin of the upper at the opposite sides of the toe with the toe of the upper outspread substantially in a plane, said grippers being movable inwardly toward the form in fixed paths in the upper-shaping operation in response to the pull of the upper thereon while holding the portions of the upper which they engage from uncontrolled movement lengthwise of the form.

12. In a machine of the class described, the combination with means for upwiping the toe of an untensioned upper over the end and the sides of a form substantially to

the shape desired for the finished shoe, of grippers for gripping the margin of the upper substantially at the ends of the tip seam and for holding the portions thus gripped from shifting lengthwise of the form in the upwiping operation.

13. In a machine of the class described, the combination with means for clamping the margin of the toe of an upper and for shaping the upper over a form while permitting the clamped margin to slip inwardly toward the form in response to tensions arising in the upper, of grippers for gripping the margin of the upper at its opposite sides at the rear of the clamped portion, said grippers being movable inwardly toward the form in response to the pull of the upper while preventing uncontrolled movement lengthwise of the form of the portions of the upper which they engage.

14. In a machine of the class described, the combination with means for shaping the toe portion of an upper over the end and the sides of a form comprising mechanism for clamping the margin of the upper about the toe while permitting it to slip inwardly toward the form in response to tensions arising in the upper as it is shaped over the form, of grippers for gripping the margin of the upper substantially at the ends of the tip seam and for holding the portions thus gripped from slipping, said grippers being mounted to move inwardly toward the form in fixed paths in response to the pull of the upper thereon.

15. In a machine of the class described, the combination with means for shaping the toe portion of an upper over a form, comprising wipers for wiping the margin of the upper inwardly over the form and means for clamping the margin of the upper upon said wipers while permitting it to slip inwardly toward the form in response to tensions arising in the upper, of grippers for gripping the margin of the upper substantially at the ends of the tip seam, said grippers being movable inwardly toward the form in response to the pull of the upper thereon while preventing displacement lengthwise of the form of the portions of the upper which they engage.

16. In a machine of the class described, the combination with means for shaping the toe portion of an upper over a form, of means for positioning the upper in predetermined relation to said upper-shaping means by engaging it in jig holes provided in its margin at the opposite sides of the toe, and means for engaging the margin of the upper at the opposite sides of the toe after the upper has been thus positioned and for holding the portions thus engaged from uncontrolled movement lengthwise of the form in the upper shaping operation.

17. In a machine of the class described, the

combination with means for shaping the toe portion of an upper over a form, of means for positioning the upper in predetermined relation to said upper-shaping means by engaging it in jig holes provided in its margin at the opposite sides of the toe, and grippers for gripping the upper adjacent to said jig holes after the upper has been thus positioned and for holding the portions thus gripped from shifting lengthwise of the form in the upper-shaping operation.

18. In a machine of the class described, the combination with means for shaping the toe portion of an upper over a form, of means for positioning the upper in predetermined relation to said upper-shaping means by engaging it in jig holes provided in its margin at the opposite sides of the toe, grippers for gripping the upper substantially at the ends of the tip seam after the upper has been thus positioned, said grippers being movable inwardly toward the form in response to the pull of the upper thereon in the upper-shaping operation, and means constraining said grippers to move toward the form in predetermined directions unaffected by the directions of the tensions arising in the upper.

19. In a machine for shaping the toe of an upper over a form, means for clamping the margin of the upper outspread substantially in a plane about the form while permitting it to slip inwardly toward the form in response to tensions arising in the upper as it is shaped over the form, said clamping means comprising a member having a generally plane upper-engaging face with a plurality of grooves therein directed outwardly from the form and affording spaces for the formation of pleats as the margin is drawn inwardly toward the form.

20. A machine for shaping the toe of an upper over a form having, in combination, wipers for wiping the upper about the toe inwardly over the form to provide thereon a flange adapted for attachment to an insole, and means for clamping the margin of the upper outspread substantially in a plane upon the outer face of said wipers while permitting it to slip inwardly toward the form in response to tensions arising in the upper, said clamping means having a plane upper-engaging face with a plurality of grooves therein directed outwardly from the form and affording spaces for the formation of pleats as the margin is drawn inwardly toward the form.

21. A machine for shaping the toe of an upper over a form having, in combination, wipers for wiping the margin of the upper about the toe inwardly over the form, means for clamping the margin of the upper outspread substantially in a plane upon the outer face of said wipers while permitting it to slip inwardly toward the form in re-

sponse to tensions arising in the upper, and means for effecting while the upper is thus clamped relative movement between the form and said wipers and clamping means heightwise of the form to draw the upper over the form and thereafter movement of the wipers inwardly toward the form, said clamping means having in its upper-engaging face a plurality of grooves directed outwardly from the form and affording spaces for the formation of pleats as the upper is drawn over the form and its margin is wiped inwardly.

22. A machine for shaping the toe of an upper over a form having, in combination, wipers for wiping the margin of the upper about the toe inwardly over the form, means for clamping the margin of the upper outspread substantially in a plane upon the outer face of said wipers while permitting it to slip inwardly toward the form in response to tensions arising in the upper, said clamping means having in its upper-engaging face a plurality of grooves directed outwardly from the form and affording spaces for the formation of pleats in the margin of the upper, means for effecting relative movement between the form and said wipers and clamping means height-wise of the form to draw the upper over the form and thereafter movement of the wipers inwardly toward the form, and means for relaxing the clamping pressure while still maintaining the clamping means in clamping position as the wipers are moved inwardly toward the form.

23. A machine for shaping the toe of an upper over a form having, in combination, wipers for wiping the upper inwardly over the form to provide a flange adapted for attachment to an insole, and means for clamping the margin of the upper outspread substantially in a plane upon the outer face of said wipers while permitting it to slip inwardly toward the form in response to tensions arising in the upper, said clamping means having a generally plane upper-engaging face provided with a plurality of grooves directed outwardly from the form and affording spaces for the formation of pleats as the margin is drawn inwardly toward the form, said grooves terminating short of that edge of the clamping means which is nearest to the wiping edges of the wipers.

24. A machine for shaping the toe of an upper over a form having, in combination, means for clamping the margin of the upper about the toe while permitting it to slip inwardly toward the form in response to tensions arising in the upper as it is shaped over the form, said clamping means having therein a plurality of grooves affording spaces for the formation of pleats as the margin is drawn inwardly toward the form, and means for engaging the margin of the

upper at the opposite sides of the toe at the rear of the clamped portion and for holding the portions thus engaged from shifting lengthwise of the form in the upper-shaping operation.

25. A machine for shaping the toe of an upper over a form having, in combination, means for clamping the margin of the upper about the toe while permitting it to slip 10 inwardly toward the form in response to tensions arising in the upper as it is shaped over the form, said clamping means having therein a plurality of grooves affording spaces for the formation of pleats as the 15 margin is drawn inwardly toward the form, and grippers for gripping the margin of the upper at the rear of the clamped portion substantially at the ends of the tip seam, said grippers being movable inwardly toward the form in fixed paths in response to 20 the pull of the upper thereon while holding the portions of the upper which they engage from uncontrolled movement lengthwise of the form.

26. A machine for shaping the toe of an upper over a form having, in combination, wipers for wiping the margin of the upper inwardly over the form to provide a flange adapted for attachment to an insole, means 30 for clamping the margin of the upper outspread over the outer face of the wipers while permitting it to slip inwardly toward the form in response to tensions arising in the upper, said clamping means having 35 therein a plurality of grooves affording spaces for the formation of pleats as the margin is drawn inwardly toward the form, and means for gripping the margin of the upper at the rear of the clamped portion 40 substantially at the ends of the tip seam and for holding the portions thus gripped from uncontrolled movement lengthwise of the form in the upper-shaping operation.

27. In a machine of the class described, 45 the combination with a form, and means for molding the toe portion of an upper off the last over said form substantially to the shape desired for the finished shoe, of means for engaging the margin of the upper at the 50 opposite sides of the toe and for holding the portions thus engaged from shifting lengthwise of the form in the molding operation.

28. In a machine of the class described, the 55 combination with a form, and means for molding the toe portion of an upper off the last over said form substantially to the shape desired for the finished shoe, of members for engaging the margin of the upper 60 substantially at the ends of the tip seam and for holding the portions thus engaged from uncontrolled movement lengthwise of the form in the molding operation, said members being movable inwardly toward

the form in response to the pull of the upper 65 thereon.

29. In a machine of the class described, the combination with a form, and means for molding the toe portion of an upper off the last over said form substantially to the shape 70 desired for the finished shoe, of grippers for gripping the margin of the upper at the opposite sides of the toe and for holding the portions thus gripped from uncontrolled movement lengthwise of the form 75 in the molding operation, and spring means against the resistance of which said grippers are movable inwardly toward the form in response to the pull of the upper thereon as the upper is molded over the form. 80

30. In a machine of the class described, the combination with a form, and means for molding the toe portion of an upper off the last over said form substantially to the shape 85 desired for the finished shoe, of grippers for gripping the margin of the upper substantially at the ends of the tip seam, said grippers being mounted for movement inwardly toward the form in response to the pull of the upper thereon in fixed paths 90 such as to prevent displacement lengthwise of the form of the portions of the upper which they engage.

31. In a machine of the class described, 95 the combination with a form, means for molding the toe portion of an upper off the last over the end and side faces of the form, and wipers for wiping the margin of the upper inwardly over the form to mold thereon a flange adapted for attachment to an insole, of means for gripping the margin of the upper at the opposite sides of the toe and for holding the portions thus gripped from uncontrolled movement 100 lengthwise of the form as the upper is molded over the end and sides of the form and during a portion at least of the inward movement of the wipers. 105

32. In a machine of the class described, 110 the combination with a form, means for molding the toe portion of an upper off the last over the end and side faces of the form, and wipers for wiping the margin of the upper inwardly over the form to mold thereon a flange adapted for attachment to an insole, of grippers for gripping the margin of the upper adjacent to the wipers and for holding the portions thus gripped from uncontrolled movement lengthwise of 115 the form, said grippers being movable inwardly toward the form in fixed paths in response to the pull of the upper thereon, and yielding means against the resistance of which the grippers are thus movable. 120

33. In a machine of the class described, 125 the combination with a form, means for molding the toe portion of an upper off the last over the end and side faces of the

form, and wipers for wiping the margin of the upper inwardly over the form to mold thereon, a flange adapted for attachment to an insole, of grippers for gripping the margin of the upper substantially at the ends of the tip seam and for holding the portions thus gripped from uncontrolled movement lengthwise of the form in the molding operation, and means for maintaining said grippers in gripping engagement with the upper until after the wipers have begun to wipe the upper inwardly over the form.

34. In a machine of the class described, the combination with a form and wiping means relatively movable heightwise of the form to wipe the toe portion of an upper off the last over the end and the sides of the form, of grippers for gripping the margin of the upper at the opposite sides of the toe and for holding the portions thus gripped from uncontrolled movement lengthwise of the form in the wiping operation, said grippers being movable inwardly toward the form in predetermined paths in response to the pull of the upper thereon, and spring means against the resistance of which the grippers are thus inwardly movable.

35. In a machine of the class described, the combination with a form and wiping means relatively movable height-wise of the form to wipe the toe portion of an upper off the last over the end and the sides of the form, and wipers for wiping the margin of the upper inwardly over the form to mold thereon a flange adapted for attachment to an insole, of grippers for gripping the margin of the upper at the opposite sides of the toe and for holding the portions thus gripped from uncontrolled movement lengthwise of the form as the upper is wiped about the end and the sides of the form and during a portion at least of the inward movement of the wipers.

36. In a machine of the class described, the combination with means for shaping the toe portion of an upper over a form, and a form mounted for swinging movement relatively to said upper-shaping means to render said means effective on the upper, of a member for engaging the top of the forepart of the upper and for pressing it against the form, said member being mounted to swing about the same axis as the form.

37. In a machine of the class described, the combination with means for wiping the toe portion of an upper over the end and the sides of a form, and a form mounted for swinging movement relatively to said wiping means to render said means effective on the upper, of a member arranged to engage the top of the forepart of the upper and to press the upper against the form

during the wiping operation, said member having its upper-engaging face substantially complementary in contour to the corresponding face of the form and being mounted to swing about the same axis as the form.

38. In a machine of the class described, the combination with means for shaping an upper over a form, of co-operating inner and outer form members arranged to clamp an upper between them, said members being mounted to swing about the same axis relatively to said upper-shaping means to render said means effective on the upper.

39. In a machine of the class described, the combination with means for upwiping the toe of an upper over a form, and means for thereafter wiping the margin of the upper inwardly over the form, of mechanism automatically operative to increase the pressure of said upwiping means upon the upper after the upwiping operation has been substantially completed and for holding the upper under the increased pressure as its margin is wiped inwardly.

40. In a machine of the class described, the combination with a toe band for embracing the toe of an upper about the end of a form, means for effecting relative movement of said toe band and the form to upwipe the upper, and wipers movable to wipe the margin of the upper inwardly over the form, of automatic operating means for said toe band constructed to close the band more tightly about the toe after the upwiping operation has been substantially completed and to hold it thus closed during a portion at least of the inward movement of the wipers.

41. In a machine of the class described, the combination of an upwiping device for engaging the toe of an upper about the end of a form and for upwiping the upper in response to relative movement of said device and the form, wipers for wiping the margin of the upper inwardly over the form, means for clamping the margin of the upper on the wipers while permitting it to slip in the upwiping operation to assist in tightening the upper over the form, means for relaxing the clamping pressure substantially at the end of the upwiping operation, and automatic means for increasing the pressure of the upwiping device on the upper substantially at the end of the upwiping operation and before the clamping pressure is thus relaxed.

42. In a machine for molding the toe of an upper off the last substantially to the shape desired for the finished shoe, the combination of a form, an upwiping device, means for effecting relative movement of said device and the form to upwipe the upper, wipers for wiping the margin of the upper inwardly over the form, means for clamping the margin of the upper on the wipers while permitting it to slip in the

- upwiping operation to assist in tightening the upper over the form, means for relaxing the clamping pressure on the margin of the upper substantially at the end of the 5 upwiping operation, and automatic means for increasing the pressure of the upwiping device on the upper substantially at the end of the upwiping operation to assist in holding the upper when the clamping pressure 10 is relaxed and for relaxing the pressure of said device on the upper after the margin of the upper has been wiped inwardly and while the wipers maintain their pressure on said margin.
- 15 43. In a machine of the class described, the combination with means for molding an upper off the last over a form, and a form mounted for movement toward said molding means and thereafter away from said means,

of mechanism automatically operative in the 20 movement of the form away from the molding means to detach the molded upper from the form.

44. In a machine of the class described, the combination with means for molding the 25 toe of an upper over a form, and a form mounted for movement toward said molding means and thereafter away from said means, of a member arranged to be projected from the upper-shaping face of said 30 form, and mechanism automatically operative in response to movement of the form away from the molding means to impart to said member movement to detach the molded toe from the form.

In testimony whereof I have signed my name to this specification.

WILLIAM C. BAXTER.
